UNITED STATES PATENT OFFICE.

WILLIAM E. LANE, OF KANSAS CITY, MISSOURI.

ERASER AND PENCIL HOLDER.

1,176,909.

Specification of Letters Patent. Patented Mar. 28, 1916.

Application filed April 28, 1915. Serial No. 24,542.

To all whom it may concern:

Be it known that I, WILLIAM E. LANE, a citizen of the United States, residing at Kansas City, in the county of Jackson and 5 State of Missouri, have invented new and useful Improvements in Eraser and Pencil Holders, of which the following is a specification.

This invention is an improved eraser and 10 pencil holder the object of the invention being to provide a holder which is especially adapted for use in connection with a relatively long cylindrical eraser and by means of which the eraser may be incased, with its 15 outer end exposed and by means of which the eraser as it wears may be adjusted lengthwise from time to time to expose new outer end surfaces for use; a further object of the invention being to provide the holder 20 with improved means for holding the eraser in adjusted position and also for affording a grip for the holder to facilitate its use; a further object of the invention being to provide the holder with means for adjust- 25 ably securing a pencil therein.

The invention consists in the construction, combination and arrangement of devices hereinafter described and claimed.

In the accompanying drawings;—Figure 30 1 is an end elevation, with a portion broken away and in section, of an eraser and pencil holder constructed in accordance with my invention. Fig. 2 is a longitudinal sectional view of the same. Figs. 3 and 4 are trans- 35 verse sectional views of the same taken respectively on the planes indicated by the lines *a—a* and *b—b* of Fig. 2. Fig. 5 is a similar view, taken on the plane indicated by the line *c—c* of Fig. 1.

40 In the embodiment of my invention I provide a tubular body 1, of suitable dimensions, and made of resilient material, such for instance thin sheet metal. The intermediate portion 2 of the body or holder is hex- 45 agonal or of other polygonal form, cross sectionally, to prevent the same from rolling when placed on a desk or the like and the ends 3, 4 of the holder are of somewhat reduced diameter and cylindrical, the cylindrical end 3 being adapted to receive an

eraser 5 and the cylindrical end 4 being adapted to receive a pencil 6.

The cylindrical end 3 is provided, preferably on opposite sides, with two pairs of spaced longitudinal slits 7 which terminate 55 short of the outer end of the portion 3 and between which slits the material is provided with outwardly extending and longitudinally bowed or rounded ridges 8 whereby the tongues or strips 9 formed between 60 said slits are caused to constitute gripping members for engaging the eraser and which are adapted to be flexed inwardly so as to cause them to firmly grip and hold the eraser in place. To facilitate the action of 65 the gripping members of the holder the peripheral surface of the eraser is preferably milled from end to end as at 10. To thus press the gripping members inwardly and engage them with the eraser, to hold the latter in adjusted position, I provide a cylindrical collar 11 which is adapted to slip over the cylindrical end 3 of the holder and over the ridges 8 and which while pressing the gripping members 9 inwardly is held 70 near the inner end of the portion 3 of the holder by the said ridges 8, which act as cams, as shown. The collar has a centrally located milled annulus 12 to form a grip to facilitate holding the eraser holder in the 75 fingers and also facilitate the use of the same.

The end 4 of the holder has longitudinal slits 13 to provide two resilient oppositely arranged semi-cylindrical jaws 14 between which the pencil 6 is gripped and which 85 enable the pencil to be adjusted longitudinally from time to time as desired.

It will be evident from the foregoing description and by reference to the drawings that the major portion of the relatively 90 long eraser is incased in the holder, only the outer end of the eraser being exposed, and it will be also understood that the eraser may be adjusted from time to time as the same becomes worn by use.

Having thus described my invention I 95 claim:

An eraser holder having a tubular end portion to receive an eraser and provided with spaced longitudinal slits and ridges be- 100

tween the slits and forming cams, said slits and ridges terminating short of the end of said tubular portion, in combination with a collar fitted on said tubular portion and 5 slideable over the same and said ridges, the portions of the holder between the slits and provided with the ridges forming gripping elements which are adapted to be flexed un-

der pressure and caused by the collar to detachably grip the eraser.

In testimony whereof I affix my signature in presence of two witnesses.

WILLIAM E. LANE.
